UNITED STATES PATENT OFFICE.

FREDRIK LJUNGSTRÖM, OF FINSPÅNG, SWEDEN, ASSIGNOR TO AKTIEBOLAGET
LJUNGSTRÖMS ÅNGTURBIN, OF FINSPÅNG, SWEDEN.

ELECTRICAL MACHINE.

1,147,107.

Specification of Letters Patent. Patented July 20, 1915.

Application filed March 30, 1914. Serial No. 828,306.

To all whom it may concern:

Be it known that I, FREDRIK LJUNGSTRÖM, a subject of the King of Sweden, and a citizen of Sweden, residing at Finspång, 5 in the Kingdom of Sweden, have invented certain new and useful Improvements in or Relating to Electrical Machines, of which the following is a specification.

It has been proposed before to attach the 10 windings in electrical machines by providing them with dove-tailed projections or the like, coöperating with notches formed in a corresponding manner in the rotatable body, or in special parts jointed to the said body. 15 In such a construction it is a matter of the greatest importance that the projections and notches should be adapted to allow without difficulty the dilatation arising from the heating of the two bodies consisting respectively of iron and copper and joined together. This is obtained according to the 20 present invention by forming the parts joining the winding to the rotating body in such a way as to prevent a mutual displacement. 25 in any radial direction with regard to the center of the rotating body but to allow the displacement longitudinally of the winding.

The invention is an improvement on the construction shown in my Patent #1,115, 30 220, though available for use with magnets differing in some respects therefrom and is illustrated in the annexed drawings in a construction having dove-tailed parts joining the winding and the armature body.

Figure 1 represents a cross section of a 35 part of the rotating body and a part of the winding thereon, the said parts embodying my invention; Fig. 2 represents on a larger 40 scale a similar view of a modified construction of the same omitting the insulation and metal surfaces; and Fig. 3 represents a still further enlarged portion of Fig. 2, showing also the insulation and metal faces.

In Fig. 1 *a* is the winding and *a'* are the 45 projections attached thereto and entering the notches between the projections *b'* of the rotatable body *b*. The projections *a'* and *b'* are provided with step form smaller 50 projections constructed according to the present invention to allow the surfaces *c* and *d* placed in the longitudinal direction of the winding at right angles to the longitudinal axes of the projections *a'* *b'* to rest against each other, while the surfaces *e* and 55 *f* do not abut against each other. It is evi-

dent that hereby a free dilatation of the winding can take place longitudinally of the winding, avoiding detrimental strains. Between the surfaces *c* and *d* the necessary insulating layer *g* is put in (Fig. 3), consisting for instance of paper, mica, press-board or the like. In order to strengthen this layer, two metal covers *h* and *i* are laid in joined to *b'* and *a'* respectively. During unequal expansion of the winding and the 60 rotating body in the direction of the length of said winding the covers *h* and *i* slide over each other. In order to facilitate this sliding these two metal covers may consist of different metals as for instance, iron and 65 brass.

k is an air-layer between *f* and *e*.

In the case of the surfaces *c* being quite even and smooth the covers *h* can be omitted.

It is evident that the projections *a'* and 75 *b'* may be shaped in any manner; it is essential, however, that the shape should allow winding in the direction corresponding to the faces *d* and *e* of the steps.

What I claim is:—

1. In an electrical machine, the combination of a rotatable body with a winding thereon, these two parts being provided with alternately arranged projections having parts which engage in a radial direction with respect to said body, but which are adapted to allow displacement in the longitudinal direction of the winding.

2. In an electrical machine, the combination of a rotatable body with a winding 85 thereon, these two parts being provided with projections which have smaller step-form projections on their proximate sides, the latter projections having faces which extend in the longitudinal direction of the winding, as well as other faces which extend in other 90 directions, the former faces of the proximate step-form projections of the said body and of the winding being adapted to rest upon and slide over each other.

3. In an electrical machine, the combination of a rotatable body with a winding thereon, these two parts being provided with projections which have smaller step-form projections on their proximate sides, the latter projections having inclined faces which are arranged with an interval between them and also faces extending in the longitudinal direction of the winding, which faces rest upon and slide over each other.

4. In an electrical machine, the combination of a rotatable body and a winding thereon, said parts having alternately arranged projections provided with smaller step-form projections on their proximate sides, with an interposed insulating layer and interposed metallic covers, said step-form projections having faces which extend in the longitudinal direction of the winding and inclined faces with a space left between each opposed pair of faces, of the covers on the former faces being adapted to slip over each other.

5. In an electrical machine, the combination of a rotatable body and a winding thereon, with an interposed insulating layer and metal covers, the said body and winding being provided with alternately ar-

ranged projections having step-form projections on their sides, which are constructed with faces that extend in the longitudinal direction of the winding and with additional faces adapted and arranged to permit a displacement of said parts by expansion in the longitudinal direction of the winding, the said metal covers fitting on said step form projections and sliding over each other where they fit on the former faces.

In testimony whereof I have affixed my signature in presence of two witnesses.

FREDRIK LJUNGSTRÖM.
